UNITED STATES PATENT OFFICE.

LAURENCE L. SCHOMO, OF SAYRE, PENNSYLVANIA.

DOOR-HOLDER.

1,263,128.

Specification of Letters Patent. Patented Apr. 16, 1918.

Application filed October 27, 1917. Serial No. 198,818.

To all whom it may concern:

Be it known that I, LAURENCE L. SCHOMO, a citizen of the United States, residing at Sayre, in the county of Bradford and State 5 of Pennsylvania, have invented certain new and useful Improvements in Door-Holders, of which the following is a specification.

This invention relates to door holders or fasteners and more particularly to devices 10 of this character for use in holding open the doors of railway cars but which are applicable for use in other places.

The object of the invention is to provide a simply constructed and efficient device of 15 this character whereby a door will be securely yet yieldably held in open position and thereby prevented from accidental closing and yet be releasable on the exertion of a pulling force.

20 Briefly described, the fastener consists of a resilient socket member to be mounted on the wall against which the door opens and a headed latch member carried by the door and positioned to enter the socket on the 25 opening of the door and hold the door open, but which may be readily released by the mere act of pulling the door shut.

With the foregoing and other objects in view, which will appear as the description 30 proceeds, the invention resides in the combination and arrangement of parts and in the details of construction hereinafter described and claimed, it being understood that changes in the precise embodiment of the 35 invention herein disclosed may be made within the scope of what is claimed without departing from the spirit of the invention.

In the accompanying drawings:—

Figure 1 represents a plan view of this 40 improved fastener shown in applied position with a door held open,

Fig. 2 is a bottom plan view of the latch member,

Fig. 3 is an end view of the fastener shown 45 in operative position,

Fig. 4 is a vertical section taken on the line 4—4 of Fig. 1, and

Fig. 5 is a horizontal section taken on the line 5—5 of Fig. 1.

50 In the embodiment illustrated a socket member 1 is shown mounted on a wall W against which a door D is designed to open. This socket member comprises a base plate 2 having apertured ears 3 for the passage 55 of the fastening bolts 4 which connect this member to the wall.

Extending forwardly from the front face of the base plate 2 are a pair of spaced arms 5 and 6, one of which has a projection 7 near its free end on its inner face as is shown 60 clearly in Fig. 1 and which is designed for a purpose presently to be described. The other arm 5 has a threaded opening 8 therein, through which passes a bolt 9 secured in adjusted position by a lock nut 10 and on 65 which is mounted a coiled spring 11, a washer 12 being shown arranged between said spring and the inner face of arm 5. This coiled spring 11 is also mounted on a pin 13 which projects from a tongue 14 carried by the base plate 2. This tongue 14 is here shown substantially L-shaped and the short arm 15 thereof is connected with the base plate 2 by suitable fastening elements indicated at 16 in Fig. 1, said element being 70 here shown in the form of bolts with their heads countersunk in the outer face of the base plate and their free ends provided with lock nuts 17. The long arm 18 of the tongue 14 is shown slightly inclined for a portion 75 of its length and then arranged straight for the remainder with its terminal deflected as shown at 19. This deflected terminal 19 extends toward the arm 5 of the socket member, a flared mouth being provided between 80 it and the inclined edge 7' of arm 6 so as to facilitate the insertion of the latch 20 carried by a casting 21 on the door D.

It will thus be seen that the spring 11 exerts its tension to force the tongue 14 toward arm 6 and the tension of this spring 90 may be adjusted by adjusting the bolt 9 in a manner which is obvious. The tongue 14 will thus be yieldably supported and will permit the head 22 of the latch 20 to enter 95 between it and arm 6 and to be yieldably held between them by the engagement of the projection 7 with a recess 23 formed at the inner end of the head 22 on one side thereof as is shown clearly in Fig. 1.

100 The latch carrying casting 21 is secured to the door D by apertured ears 24 through which fastening bolts 25 are designed to pass. The latch 20 has its shank 26 disposed in a socket 27 formed in the inner face of 105 the casting 21, said socket being larger than the shank to permit pivotal movement of the latch 20. A pintle 28 extends through the socket in the casting 21 and through the inner end of the shank of latch 20, and is held 110 in operative position by a cotter pin 29 or other suitable fastening.

With the parts constructed as above described, the latch member being carried by the door and the socket member by the wall against which the door opens, and properly positioned to receive the latch 20, the opening of the door will cause the head of said latch to pass into a socket 30 formed between the tongue 14 and the inner face of arm 6, said latch member having a pointed nose 31 to facilitate its entrance between said parts. When the door reaches its extreme open position the head of the latch will have entered the socket 30 and the projection 7 on arm 6 will have engaged the recess 28 in said head, the yieldable tongue 14 under the action of its spring 11 releasably holding said latch in engagement with arm 6 thereby insuring the retention of the door against accidental closing. When it is desired to close the door, all that is necessary is to exert a pull in the usual manner when the latch 20 will pass out of the socket 30 against the tension of spring 11 and the door may be closed in the usual manner.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

Copies of this patent may be obtained for five cents each, by addressing the "Commissioner of Patents, Washington, D. C."

I claim:—

1. In a door holder of the class described, a member having a latch extending laterally therefrom and provided with a projection, a catch member comprising a base plate having laterally spaced parallel arms one of which has a projection for interlocking engagement with the projection on said latch, a tongue carried by said plate and positioned between said arms, a coiled spring disposed between the free end of said tongue and one of said arms whereby the tongue is yieldably forced toward the other arm for engagement with said latch to hold the latch in engagement with said arm.

2. In a door holder of the class described, a member having a latch extending laterally therefrom and provided with a projection, a catch member comprising a base plate having laterally spaced parallel fixed arms, one of which has a projection for interlocking engagement with the projection on said latch, a tongue carried by said plate and positioned between said arms, a coiled spring disposed between the free end of said tongue and one of said arms whereby the tongue is yieldably forced toward the other arm for engagement with said latch to hold the latch in engagement with said arm, and means for adjusting the tension of said spring.

In testimony whereof I affix my signature in presence of two witnesses.

LAURENCE L. SCHOMO.
